UNITED STATES PATENT OFFICE.

ISAAC RISLEY, OF NEW YORK, N. Y., ASSIGNOR, BY MESNE ASSIGNMENTS, TO JOSEPH H. BORTON, TRUSTEE, OF ATLANTIC CITY, NEW JERSEY.

MACHINE FOR JUSTIFYING TYPOGRAPHIC IMPRESSIONS.

SPECIFICATION forming part of Letters Patent No. 588,087, dated August 10, 1897.

Application filed June 6, 1889. Serial No. 313,286. (No model.)

To all whom it may concern:

Be it known that I, ISAAC RISLEY, a citizen of the United States, and a resident of New York city, New York, have invented an Improved Machine for Typographical Purposes, of which the following is a specification.

The object of my invention is to record or register the number of word-spaces and of units in a line of printed or type-written matter during the composition of the matter and to add to or subtract from the word-spaces of the line prior to the final representation, a further object of my invention being to compose and represent upon suitable representation-paper simultaneously with making a readable impression, so that proof-corrections may be made prior to final representation.

In the accompanying drawings, Figure 1^A is a plan view of one half of the machine embodying my invention. Fig. 1^B is a plan view of the remaining half. Fig. 2^A is a transverse section on the line 1 2, Fig. 1^A; Fig. 2^B, a transverse section on the line 3 4, Fig. 1^B. Fig. 3 is a face view of the machine, partly in section, with parts of the device left out in order to prevent confusion. Fig. 4 is a diagram plan view showing the electrical connections. Fig. 5 is a plan view of a portion of the variable-feed mechanism; and Fig. 6 is a section 30 on the line 5 6, Fig. 5. Fig. 7 is a view of one of the levers.

In illustrating the mechanism in order to describe clearly my invention I have deemed it best to enlarge the drawings as much as possible, and therefore have placed Figs. 1 and 2 on two sheets each, one half of each figure being on one sheet and the other half on another sheet, and have marked the figures 1^A and 1^B and 2^A and 2^B, and in order to still further simplify the description of the machine I will divide the specification and describe the machine under special headings, as follows: first, the keyboard mechanism; second, the final representation or impression mechanism; third, the feed for the final representation or impression mechanism; fourth, the unit-recording mechanism; fifth, the space-recording mechanism; sixth, the line-recording mechanism; seventh, justifying-50 keys.

The keyboard and mechanism connected therewith.—This keyboard is substantially the same as a keyboard of a type-writer or analogous machines, in which by pressing a key a certain impression is made, depending upon the key pressed. Each key is carried by a lever which is connected to certain operating mechanism described hereinafter, and in describing my invention I simply allude to one key-lever and mechanism connected therewith, as it will be unnecessary to complicate the specification by alluding to the series.

A is the key-lever, pivoted to a common pivot-bar A', and extending beyond the pivot A' is an arm A², having a knife-edge a, which strikes against the cutter-bar B, described hereinafter. A spring a', connected to a cross-bar a², tends to keep the lever raised in the position shown in Fig. 2^A.

The representation-paper H passes under the cutting-bar B, and as the key is moved by finger-pressure the knife-edge passes through the paper, thus making an incision or perforation until coming in contact with the cutting-bar B. A spring J' on the cross-bar J² tends to keep the paper always in contact with the cutter-bar.

Each character-key is connected to a type-lever A³, pivoted at a³ in suitable bearings on the frame, the type-levers being connected to the key-levers each by a rod A⁴, so that as each key-lever is pressed it will throw its type A⁵ into position under the proof-ribbon E and inking-ribbon F, described hereinafter, making the proper impression on the proof-ribbon. This proof-impression is made simultaneously with the incision of the representation-paper by the knife-edge a, so that it will be seen that each character as it is impressed makes two independent representations, one being a readable character-representation, while the other is a representation consisting of an incision in the representation-paper H, said incisions being of such a character that when the paper passes upon the second bar mechanism is so thrown into operation as to effect the formation of the final impression, as fully described herein-after.

The characters vary in size, being graded by what is known as "unit-measurement." In the present case they vary from two to five units, according to the width of the type. 5 For instance, the two-unit letters include such letters as "i" and the several punctuation-characters, while the five-unit characters are such letters as "M" and "W" of the upper case. In this instance the single unit is not 10 used in the type-representation, but only for a purpose described hereinafter.

The normal word-space is represented as three units, so that in the justification, described hereinafter, units may be subtracted 15 from or added to this normal space, as determined by the length of line prior to justification.

In order to carry out the unit system and to register or record the units properly, the 20 following arrangement is made: $A^5 A^6 A^7 A^8$ are four transverse rock-shafts, and secured to these rock-shafts are levers $a^5 a^6 a^7 a^8$, which come in contact with unit-lugs 1 2 3 4 on a rod a^4 , having a pawl at its upper end 25 which engages with a unit-recorder ratchet-wheel, described hereinafter. On each shaft A^5 to A^8 are levers A^9 , connected to their respective key-levers A through links a^9 , so that if, for instance, the key-lever A is pressed 30 this lever may be the lever of the letter "M," upper case, in which instance it is connected to the arm A^9 on the rock-shaft A^8 , which carries the arm a^8 , bearing against the unit-lug 4, moving the registration-wheel five units. 35 Pivoted to the shaft A' are levers A^{10} , Fig. 7, each of which is connected by a link a^{10} to a corresponding lever-arm A^9 on one of the shafts $A^5 A^6 A^7 A^8$. Each lever A^{10} is carried beyond its pivot to form an arm A^2 , 40 which is provided with a knife-edge a^2 , the same as that of the key-levers A . These levers A^{10} cause to be represented, by incisions or perforations on the representation-paper H , the spaces taken up by the different 45 characters, whether one, two, or more units, so that the feed of the matrix-carriage or final-representation carriage will be regulated at the proper time in respect to the impression of each character upon the matrix or final- 50 representation sheet.

Extending underneath and in contact with the key-levers A is a feed-bar B' , pivoted also to the shaft A' . On the bar B' is an arm B^3 , connected to the ratchet-feed mechanism B^4 55 for the representation-paper H , so that as each key or character lever is pressed this pressure is transferred to the paper-feed, so that the paper will be fed a certain distance at each incision or impression. This bar B' has also 60 an arm B^2 , connected to a pawl b , which acts upon a ratchet F' , pivoted at f , to feed the inking-ribbon F of the proof mechanism.

C is a space-key lever pivoted to a shaft C' , and has an arm C^2 , connected by a link c 65 to a lever C^3 , hung to the pivot-rod A' . This lever has a pin c' , which bears upon the arm B^3 of the paper-feeding device, so that as the

space-key lever C is pressed it will move the paper the proper space. The lever C has a second arm C^1 , which is connected by a rod c^2 to the feed-pawl of the space-recording mechanism, described hereinafter, so that every space is properly registered or recorded upon a suitable dial. 70

There are also two keys on the keyboard, 75 one of which is the carriage-key and the other the line-key. By pressing the line-key the line-registering mechanism is operated so as to move the arrow one notch, described fully hereinafter. 80

I will now describe the mechanism by which the final impression is made.

Situated at a certain distance from the block B is a second block D . The distance between the two blocks is preferably more than the 85 length of line to be printed, as it will be understood that the mechanism composes at least one line ahead of the final-impression mechanism, so that while the operator is composing one line and making a proof thereof 90 the machine is impressing or printing the previously-composed line, as it will be understood that after a line is composed and a proof taken the operator reads the dials and sets the justifying apparatus prior to the composition of 95 a second line, but after this matter is justified the operator can start a fresh line and the machine will then take care of itself and produce a final and properly-justified line. The bar D is grooved on its under side and under 100 this grooved bar passes the paper H , which has been previously perforated. Directly under the bar D is a series of knife-edges d , each knife-edge being carried by a lever D' , mounted on a pivot-rod D^2 . There are the 105 same number of levers D' as there are key-levers A and unit-levers A^{10} . Under the levers D' is a bar d' , between which and the under side of the levers D' is a series of small 110 springs d^2 , tending to keep the levers always against the under side of the paper, so that when the perforations made by the knife-edges a pass under the bar D the levers D' will be forced through the perforations and make contact with the bar D , as the bar D is 115 a terminal of an electric circuit shown by the wire x , which extends to a battery X , Fig. 4, and is also a terminal for a circuit indicated by the wire z , which extends to the battery Z , Fig. 2^B. 120

Each of the levers D' is the other terminal for the circuit z , and the wires that are connected to the different levers D' are attached to their respective magnets G , each of the magnets being connected to a common return-wire z' to the battery Z , so that it will be seen that as soon as a perforated portion of the paper H passes under the bar D the levers D' pass through the perforations and make contact with the bar and complete the circuit 125 z , and thereby energizing the proper magnet of the series, so as to attract an armature G' on a rod G^2 , through which passes a claw-arm G^3 , having at its upper end a hook g , which 130

engages with a reciprocating bar G^4 when the armature is drawn toward the magnet, Fig. 2^b. The opposite end of this hooked arm is attached to one arm of a lever H' , 5 pivoted at h , and carrying at its opposite end the impression-type h' for making the final impression or matrix. The letter impressed by the type h' will be the proper letter, as indicated on the proof-recording ribbon as 10 well as on the representation-paper, so that the letter or character in the proof and the final impression will agree in every respect.

I will here state that the proof-type may be of different character from that of the final 15 impression and of different size, as the proof-type might be large and readable, when it is necessary to make the final impression with minute type.

The bar G^4 is reciprocated from the shaft 20 G^5 , on which are mounted eccentrics G^6 , connected to the bar at g' , so that as the shaft revolves the eccentrics give the bar the proper reciprocation. It will thus be seen that the 25 bar type-levers H' and the connecting-levers G^3 can be made heavy enough to withstand any amount of pressure, and consequently any depth of matrix may be made.

As shown in Fig. 4, there are five additional levers D' at the end of the shaft in line with 30 the unit-levers A^{10} , described above, which are the five-unit levers, and additional to these levers are the space, line, and carriage movement keys described above.

On the shaft G^5 is a belt G^7 , and on one of 35 the retaining-disks of the eccentric is a stop-lug g^2 , on which acts an escapement-lever g^3 , which has a reciprocatory movement toward and from the shaft as each impression is made, the lever being in this instance connected to the end of the lever of the arm B^3 , 40 so that it acts whenever the bar B' is depressed.

Pivoted to the escapement-lever at g^5 is a short lever g^4 , which forms an extension of 45 the escapement-bar g^3 , so that the shaft g^5 will turn only one revolution at each movement of the cross-bar B' . When the rod g^3 is moved in the direction of the arrow, its end will come under the lug g^2 and the end of the 50 arm g^4 will move from under the lug, and when the rod moves in the direction opposite to that shown by the arrow the lug will be released and the shaft will be revolved by the belt on the belt-wheel until the lug comes in 55 contact with the arm g^4 , which has returned to its original position. The shaft will be stopped by this lug until the operator strikes another key on the keyboard and releases the shaft, as above described.

60 The feed of the paper H is as follows: B^5 is a paper-receiving roller, the paper passing from under the bar D between two friction-rollers B^6 B^7 , the top roller B^7 being merely a bearing-roller, while the roller B^6 is driven.

65 On the end of the roller B^6 is a ratchet-wheel B^8 , acted upon by a pawl b^2 on an arm b^3 , piv-

oted to the shaft of the roller B^6 . This arm b^3 is connected to the arm B^3 by a rod b^4 . Thus it will be seen that at each movement of the arm B^3 the paper will be moved one space, as 70 clearly shown in the drawings.

I will now describe the mechanism for the final representation.

I is the final-representation or matrix cylinder, mounted on a shaft I' and carried by a 75 frame I^2 , having ratchet-teeth, as shown, and acting on these ratchet-teeth is an escapement-arm i of a hub i' , mounted on a shaft i^2 . An arm i^3 of this hub is connected to a hooked rod i^4 , the hook of which can be thrown into 80 engagement with the reciprocating bar G^4 through the medium of a magnet i^5 , which is in the circuit shown by the line z^2 , one end of this wire being connected to the line-lever D' , so that at the end of each line the magnet will 85 draw the arm i^4 and the bar G^4 will vibrate the hub i' and move the carriage one notch, as it will be remembered that in this particular construction the cylinder is turned as each letter is impressed, and is moved longitudinally after each line is completed, which is the reverse of the construction usually adopted in type-writers. A weight I^3 , attached to a cord i^6 , which is connected to the carriage I^2 and passes over a roller i^7 , tends to feed the 90 carriage in the direction of the arrow when released by the escapement.

The cylinder I slides on but turns with the shaft I' , and is turned by the dictation of the ratchet-wheels $J' J^2 J^3 J^4 J^5$, which are secured to the shaft. Pivoted to a rod J , at the side of the ratchet-wheels, is an arm J^6 , hung to which is a lever J^2 , having two arms $j j'$, one a pawl and one an armature arm, and above the armature of each lever is a magnet. There 100 are five magnets $K' K^2 K^3 K^4 K^5$. These magnets are in the circuit x , Fig. 4, which passes through the battery X , over the wire x to the plate D , which is one terminal, and through the wires $x^1 x^2 x^3 x^4 x^5$ to the levers D' on the 110 end of the shaft D^2 . These levers, as before described, have knife-edges d , which pass through perforations in the paper and make contact with the bar D and complete the circuit, so that it will be seen that if the key of 115 the letter M is pressed it punctures the paper to make the final impression M , and likewise makes an impression in the paper to represent five units on the unit-measurement column, so that as soon as this perforation comes in 120 line with the bar D the lever D' , representing the character M , passes through the paper and makes contact with the bar D , the lever D' , representing five units, also passing through this perforation of the paper and making contact with the bar D , so that the circuit x , as well as the circuit z' , is completed, the latter picking out the final representation M , while the former energizes the magnet K^5 , lifting its lever into position in front of a vibrating arm N 125 on an upright shaft N' , which moves the five-unit ratchet J^5 the proper distance, which in

turn revolves the shaft and its drum I five units, so that the proper spacing of the characters is assured.

The vibrating arm N is connected to an eccentric-pin N² on the shaft G⁵ by a connecting-rod N³, so that as the shaft revolves by the dictation of the machine the arm N is moved forward, forcing one or other of the levers J⁷ forward, depending upon which one is moved in the line of the arm to the proper distance, whether one unit or five units.

A detent-lever N⁴, pivoted to a bar N⁵, engages with the ratchet-teeth and prevents their return movement, as clearly shown in Fig. 6. A spring n, connected to one arm of the lever and to a part of the machine, keeps the detent-lever always in gear with the ratchet. To throw the detent clear of the ratchet, however, I provide an arm n', which passes under a portion of the frame and holds the detent clear of the ratchet when circumstances require. The detent-lever N⁴ also has a bar n², extending under a series of levers J⁷, so that when the detent-lever is lifted it lifts the lever J⁷ clear of the ratchet-wheels, thus allowing the free return movement, which is effected by the spring I⁴, as clearly shown in Fig. 2^A.

I have now described the mechanism which will print a readable representation on proof-paper and will puncture, perforate, or indent a sheet of paper, which in turn makes suitable electrical connections by which the final representations, either in matrix or other final form, are made, and will so arrange the type-impressions that each letter of the final impression will be composed of a certain number of units, depending upon the width of the letter, but all the lines of the page will not be of the same length, and therefore will not be justified on the right-hand side without further manipulation. I will hereinafter describe the mechanism for justifying the line.

The several recording mechanisms.—The unit-recording mechanism (shown clearly in Figs. 2^A and 3) is operated through the vertical bar a¹, connected to an arm p, carried by a sleeve on a shaft P'. This arm p carries a pawl p', which engages with a ratchet-wheel p², fast on the shaft P'. This shaft P' carries an arm P², in which slides a pointer P³, indicating on a dial P⁴ each unit on the line being composed, so that if the key of a letter of two-unit measure is pressed two units are indicated on the dial, and if a three-unit letter is pressed three units are indicated, and so on. The dial ranges from "1" to "120," and the unit-marks are arranged in two rows, and the pointer has a pin p³, which rests in a groove, so that when it revolves from "1" to "60" it is moved so that the end of the pointer will come on the second line, and then it moves around this line, thus indicating the number of units on the line.

On the dial is a row of additional units representing twenty units from the end of the line and fifteen units beyond the end of the

line, so that if the line does not register precisely with the unit measurement, say, for instance, it comes at "115," it is five units from the end of the line, and the operator can see at a glance that he has five units to make up in spaces, but if the latter extends to, say, "125" his line is five units longer than it should be and he must subtract five units from the word-spaces. When the pointer reaches the "100" mark, it rings a bell, thus notifying the operator that there are twenty more units before the end of the line is reached, which is substantially the means employed in type-writers of ordinary construction. When the line is finished, the line-recording key R is pressed by the operator, and to this line-operating lever is connected a rod q, which releases the feeding and retaining pawls p' and p⁴. A spring attached at one end to the dial and at the other end to the pointer returns the pointer to its normal position at the unit-mark, so as to begin counting the units in a new line.

Space-recording mechanism.—In the present instance directly under the unit-recording mechanism is the space-recording mechanism S, which is acted upon by the space-key C through the medium of the vertical rod c², which is connected to the feed-pawls, pivoted to an arm S', mounted on a shaft S², which also carries a pointer s', which passes across the face of a segmental dial S⁴, with the space-indications marked thereon. Pivoted to a rod s² is a detent-pawl s³ to prevent the ratchet-wheel S³ from moving backward. When the space-key is moved through the medium of the pawls and rod c², it indicates one space, and as space after space is made in the line it is indicated on the dial by the pointer. When the line is finished, the operator notices the number of units in the line, and if there happen to be five units less than the required length of line and there are, for instance, seven word-spaces in the line he moves the justifying-keys, described hereinafter, so that the five units will be divided between five spaces, one unit added to each space, thus making five spaces of four units each and the remaining spaces three units each, so that the proper length of line is obtained.

The pawls of the space-recording mechanism are thrown out of gear by the line-lever R in the same manner as the unit-recording mechanism, and the pointer is returned to its normal position by a spring.

I will now describe the line-recording mechanism. After each line is completed the operator touches the line-recording button on the lever R, pivoted to a shaft R'. This arm carries a pawl r, which engages the teeth of a ratchet-wheel R², fast on the shaft R', and on the shaft is an indicating-pointer r', which acts in connection with a dial R³, having the line-marks thereon, so that at the end of each line by pressing upon the lever R the pointer is moved one line, and at the same time the pointers of the unit-recording mechanism and

the pointers of the space-recording mechanism are returned to their normal positions, as above described. The detent-pawl t^2 tends to prevent the ratchet from returning. Thus 5 three records are kept, first, of the lines of the page; second, of the spaces of each line, and, third, of the units composing each line, so that the operator can see at a glance the exact condition of the line before the final 10 impression is made, and although while composing the matter in advance the proof is taken immediately upon the ribbon, so that if any mistakes occur in composing the line the operator can read the proof and correct 15 the same by closing the slot made by the knife-edge at the point the mistake occurs and by making a new slot at the point required before the final impression is made.

As shown in Fig. 1¹, Q is the paragraph-key, pivoted at Q' and connected to a lever A, connected to the pivot-shaft A', and this lever is provided with a puncturing edge a, so as to puncture the paper H at the commencement of each paragraph. The puncture 20 is in line with a lever D', connected to one or other of the unit-magnets, preferably the three-unit magnet, so that when the contact is made the carriage will be moved a space of 25 three units before the first letter of the paragraph is printed or impressed.

Justifying-keys.—I will now describe the construction of the justifying-keys, through the medium of which the machine is set to justify the lines when the final impression is 30 made.

Between the keyboard of the machine and the proof-taking mechanism are situated, in the present instance, four justifying-keys T T' U U'. U is the one-unit excess or adding 35 key; U', the two-unit-adding key, and T is the one-unit-subtracting key, and T' is the two-unit-subtracting key, so that to add units to a short line the keys U U' are operated and to subtract units from a line that is longer 40 than desired the keys T T' are operated. All the keys are precisely alike with the exception of different heights of cam, so that a description of one will suffice for all.

t is a vertical shaft having a suitable handle or finger-lever t', by which the shaft is turned. This handle has a pointer t², passing over a stationary dial t³, which also acts as a bearing for the shaft.

Directly below the dial is a cam t⁴, which 55 bears against a lug u on a bar V, extending across the machine. The cams t⁴ of each of the keys T' and U' are high cams, while the cams of the keys T and U are short cams, so that if the two keys U U', for instance, are 60 moved to make a compound justification the cam of the key U' will throw the bar away from the cam of the key U and this cam will not come in contact until after the key U' has completed its work.

65 The bar V rests against a stop V' when in its normal position, and this stop is electrically connected through the wire x^{x3} with the

three-unit magnet K³, it being in the circuit indicated by the line x. The bar V is also an electric terminal for the electric circuit x 70 and is electrically connected to the space-lever D' through the medium of the wire x^{x3}, so that when the justifying-keys T T' or U U' are clear of the bar V and when a space-opening occurs in the representation-paper H 75 contact is made between the bar D and the lever D' and the current passes through the wire x^{x3}, bar V, stop V', wire x^{x3}, to the three-unit magnet K³, thence to the battery X and through the wire x to the bar D, thus completing the circuit, and consequently moving the carriage three units at the word-spaces.

Directly below each of the justifying-keys is a magnet W in the circuit x^{x3}, and directly above each magnet is an armature w on a 85 lever w', pivoted at u² and carrying an escapement-lever having two prongs w³ w⁴, which act upon double escapement-segments v on the shaft t, so that when a perforation comes under the bar D and allows the space-lever D' to come in contact with the bar the magnet W attracts its armature, and consequently moves the escapement and allows the cam and its pointer to return one point, regulated by the distance apart of the teeth on 90 the segment v. A spring v' tends to bring the cams t⁴ and the pointer t² back to their normal 95 positions.

Each key and its magnet W is connected as follows: The key T is connected to the 100 magnet K² through the wire x^{x2}, the key T' is connected to the magnet K' through the wire x^{x1}, and the key U is connected to the magnet K⁴ through the wire x^{x4}, and the key U' is connected to the magnet K⁵ through the 105 wire x^{x5}, so that the circuit when it passes through any one of the keys will pass to the corresponding magnet, attracting the unit-lever, which can act upon the ratchet-wheel on the shaft I'. 110

Thus it will be seen that when the operator finishes a line and finds that the unit-spaces in the line fall short four units and that there are four word-spaces, for instance, the one unit-key U is moved four points or units, thus 115 throwing its cam into contact with the bar V, which is pushed out of contact with the stop V', and consequently word-spaces in the line which will ordinarily represent three units will now indicate four units, owing to the 120 fact that the current passes through the wire x^{x3} to the key U, through the wire x^{x4} to the magnet K⁴, to the battery X, and, returning to the bar D, completing the circuit, the magnet K⁴ attracting the four-unit lever, 125 thus feeding the carriage four units instead of the normal three-unit feed, but if the line falls short seven units in a line having four word-spaces, for instance, the two-unit-adding key U' is moved three points, taking up 130 six of the units in the first three spaces and then moving the one-unit-adding key U one point, so that the current will pass through the bar V and through the two-unit-adding key U'

and the five-unit magnet K^5 three times, thus adding six units to the first three spaces. The cam of the key U' will then clear the bar and the bar will drop back to the single-unit cam 5 of the key U , which will add one unit to the next space, thus completing the line by adding the seven extra units. The same is the case when the line is a number of units longer than desired, when the subtracting-keys $T' T'$ 10 are brought into play, operating in substantially the same manner to subtract the units by carrying the current through the keys to the two-unit and one-unit magnets K' and K^2 , lifting the one and two unit levers, so as to 15 feed the carriage only one or two units in place of the normal three-unit movement.

I have described one construction of machine embodying my invention, but it will be evident that other forms of machines may be 20 constructed differing from the machine set forth in this specification, as mechanical means may be used in place of electrical means, and the electrical connections can be carried out to a greater extent than shown 25 herein, and the machine may be so constructed that instead of the roller I an automatic unit-moving feed-table may be provided, in which case flat matrices may be used, or the final-representation mechanism may, instead 30 of printing the character, throw in suitable mechanism by which independent types can be cast or set without departing from my invention.

I claim as my invention—

35 1. A machine for typographic purposes provided with means for producing preliminary representation, in combination with means for recording the units thereof, to govern the production of the final justified representation.

40 2. A machine for typographic purposes provided with means for producing preliminary representation, in combination with means for recording the units thereof, and a word-space record, to govern the production of the final justified representation.

45 3. A machine for typographic purposes, provided with means for producing a preliminary representation and means for recording the unit widths of the characters and of the normal word-spaces in a represented line, with means for indicating the number of units the represented line is short of its standard length.

50 55 4. A machine for typographic purposes provided with means for producing a preliminary representation and means for recording the unit widths of the characters and of the nor-

mal word-spaces in a represented line, with means for indicating the number of units the 60 represented line is in excess of its standard length.

5. A machine for typographic purposes provided with means for producing a preliminary representation, in combination with means 65 for making a readable impression, and devices for recording the units and word-spaces of said representation.

6. A machine for typographic purposes provided with means for producing a preliminary 70 representation and devices for recording the units and word-spaces of said representation in combination with a series of differential devices to control the spaces in the final representation with reference to the excess or 75 shortage in unit measurement of the preliminary representation.

7. A machine for typographic purposes provided with a unit-record and a word-space record and means to justify the line. 80

8. A machine for typographic purposes provided with unit and word-space recording devices, and means adapted to be set by the operator from the recorded indications to 85 justify the line.

9. A machine for typographic purposes provided with means for producing a preliminary representation, in combination with means for recording the number of word-spaces represented, and means to justify the line. 90

10. A machine for typographic purposes, provided with means for producing a preliminary representation both of the characters and the word-spaces, with means to justify the lines. 95

11. A machine for typographic purposes having keys and a preliminary-representation device with represented word-spaces in combination with feeding devices for the final representation and means controlled by the 100 represented word-spaces for connecting justifying-keys with the feeding devices to justify the word-spaces.

12. A machine for typographic purposes having a preliminary-representation device, 105 in combination with unit and word-space recording devices, and means adapted to be set by the operator from the recorded indications to justify the line.

In testimony whereof I have signed my 110 name to this specification in the presence of two subscribing witnesses.

ISAAC RISLEY.
